United States Patent Office

Des. 191,015
Patented Aug. 1, 1961

191,015

HOLDER FOR TAPE OR SIMILAR ARTICLE

Charles F. Bertschinger, Easthampton, William A. Crook, Belmont, and Howard N. Gold, Northampton, Mass., assignors to Chart-Pak, Incorporated, Leeds, Mass., a corporation of Connecticut

Filed Feb. 11, 1960, Ser. No. 59,356

Term of patent 14 years

(Cl. D58—11)

FIG. 1

FIG. 2

FIG. 3

FIG. 4.

The side not shown is the same as the side shown.

The dominant features of our design reside in the portions shown in full lines.

We claim:

The ornamental design for, holder for tape or similar article, substantially as shown and described.
